UNITED STATES PATENT OFFICE

MURDOCK MACDONALD, OF CLEVELAND, OHIO

TICKET HOLDER

Application filed July 27, 1927. Serial No. 208,732.

The present invention, relating as indicated to ticket holders, is particularly directed to a holder for use at ticket stations for the convenient retention of a pad or series 5 of loose leaf tickets, from which the tickets may be torn off at various lengths for various distances and rates of fare, and in which also the stubs may be conveniently retained in such a position that they do not inconvenience the further use in handling of the 10 unsold tickets in the pad.

To the accomplishment of the foregoing and related ends, said invention, then, consists of the means hereinafter fully described 15 and particularly pointed out in the claims; the annexed drawing and the following description setting forth in detail certain mechanism embodying the invention, such disclosed means constituting, however, but one 20 of various mechanical forms in which the principle of the invention may be used.

In said annexed drawing.

Fig. 1 is a side elevation of my improved ticket holder; Fig. 2 is a plan view of the 25 same; Fig. 3 is a central longitudinal section; and Fig. 4 is a plan view of one of the tickets and a portion of the stub from which it has been separated.

Referring now to Fig. 1, there is shown an 30 open U-shaped frame 1 comprising spaced upwardly extending arms 2 and 3, upon which is supported a pad-carrying plate 4, which is slightly arched, as indicated in Fig. 1, for a purpose to be presently described. 35 At one end of the holder there is mounted a bracket 6 provided with openings therein, through which slidably extend inverted U-shaped wires 7, on the lower ends of one leg of which is carried a weighted block, while 40 the other legs extend through suitable openings in the plate 4 and slide vertically in the recess 9 formed in the end member 2 of the frame.

Mounted on the plate 4 are a series of 45 tickets 11 provided with suitable openings to permit them to be passed over the shorter arms 12 of the members 7, which then hold these tickets in the position shown in Fig. 2 on top of the holder. The weight 8 draws 50 the members 7 downwardly, retaining the

tickets in the desired position until these elements are lifted, either to permit the stubs to be slipped off or a new pad of series of tickets to be placed in position.

Resting on top of the pad of tickets is an 55 open rectangular member 15 consisting of a top plate which rests directly upon the tickets, end plates 16 which extend downwardly on either side of the tickets and the plate 4; and the weighted bottom member 18 60 connecting the plates 16. Slidably mounted beneath an extension 19 on the top of the plate 13 is a pointer 20, which may be conveniently moved by means of a button or handle 21, while the forward edge 22 of the 65 plate 15 is beveled and constitutes a tearing-off edge, against which the tickets may be severed from the stubs.

A sample ticket is shown in Fig. 4, this 70 ticket being provided with columns 25, 26 and 27, the first column carrying a list of stations or stops in their proper order, and also the rates of fare for the distance between the station of issue and the station to which the ticket is sold. In the second column 26 75 the same list of stations appear, but in this column they appear one line higher than in the preceding column, thus the town of Kent appears on the fourth line of the first column and the third line of the second column. In 80 the column 27 appear the rates of fare from the station of issue to the respective stations named in the column 26. When a ticket is torn off at the point indicated in Fig. 4 the ticket will show at the torn-off edge the station to which it is sold, and the rate of fare. 85 The last-named station in the column 26 of the ticket is the station to which it will permit a passenger to ride and the rate of fare will be indicated in one of the columns 27, 29 or 30. In case the ticket is a full fare ticket, 90 a notch 28 will be formed in the column 27, whereas, if it is a half-fare ticket, or an excursion ticket, that fact will be indicated by a 95 similar notch formed in the column 29 or the column 30, respectively, such last-named column being marked on the stub as half-fare and excursion, respectively. These notches are of course formed by the pointer 100

20, which may be shifted to the desired column before the ticket is severed.

The ticket thus presents the station which is most distant from the station of issue at the 5 severed edge and the passenger cannot, by again severing the ticket, make the ticket call for any station more distant than the one for which it was purchased. The stub shows in the column 25 the station for which the balance of the ticket was issued and also the 10 rate of fare, thus making it extremely convenient for the auditor to check the tickets against the stubs and to determine the total amount of money received by the ticket seller 15 for the tickets severed from the stubs which are retained.

The member 15 may conveniently and quickly be moved along the upper surface of the pad of tickets until the tearing-off edge 20 22 is opposite the desired place on the ticket for severing, while the pointer 20 can also be easily adjusted transversely of the member 15 for notching the proper one of the columns 27, 29 and 30. By arching the supporting plate 4 the stub of each ticket as severed is caused to fly upward slightly as soon as the member 15 is moved from off the end of the same, the stub moving into the position indicated at 35 in Fig. 1, from which position it 30 can conveniently be turned over the member 7 into the position indicated at 36 in Fig. 1, the stubs then resting on the shelf 38 formed on the bracket 6. Whenever all of the tickets from the pad or series are used the stubs may 35 be conveniently removed by lifting the member 7 and sliding the stubs around these members and off from the free short ends which are then above the plate 4, after which a new series of tickets may be slipped over these ends and locked into position by dropping the member 7 into the position shown in Fig. 3.

The present holder is not only very simple in its construction, but is extremely simple and convenient to use and preserves all of the 45 stubs for subsequent checking, as well as providing a quick means of issuance of tickets to various points. Furthermore, the tickets are of such a form that it is impossible to "raise the ticket" by mutilating it, as any 50 mutilation reduces the value of the ticket and the distance for which it is valid.

Other modes of applying the principle of my invention may be employed instead of the one explained, change being made as regards 55 the mechanism herein disclosed, provided the means stated by any of the following claims or the equivalent of such stated means be employed.

I therefore particularly point out and distinctly claim as my invention:—

1. In a ticket holder, the combination of an open rectangular frame, means for removably retaining a series of tickets on the top of said frame, and a second open rectangular member embracing said tickets and the

top of said frame, said second member being movable along said tickets and serving as an edge against which the uppermost ticket may be severed.

2. In a ticket holder, the combination of an open rectangular frame, means for removably retaining a series of tickets on the top of said frame, means movably engaging against the uppermost of said series of tickets and provided with a severing edge, and means on said last-named means and adjustable with respect thereto for notching the severed ticket at a predetermined point. 70

3. In a ticket holder, the combination of an open rectangular frame, means for removably retaining a series of tickets on the top of said frame, a second open rectangular member embracing said tickets and the top of said frame, said second member being movable along said tickets and being provided with a severing edge against which the uppermost ticket may be severed, and means adjustable on said second rectangular member, said means including an element adapted to notch a severed ticket at a predetermined point. 80

4. In a ticket holder, the combination of a frame provided with a convex upper surface, means for removably retaining a series of tickets on said convex surface, and a second open rectangular member embracing said tickets and the top of said frame, said second member being adapted to maintain said tickets against said frame and being movable along said tickets to serve as a severing edge against which the uppermost ticket may be severed. 90

5. In a ticket holder, the combination of an elongated frame provided with longitudinally convex upper surface, means for removably retaining a series of tickets on said convex surface, said means including an inverted U-shaped member movably supported in said frame and extending through appropriate registered openings in said series of tickets, said member being also adapted to retain the stubs of severed tickets. 105

6. In a ticket holder, the combination of an open rectangular frame provided with a convex upper surface, means for removably retaining a series of tickets on said surface, said means including a member embracing said tickets and the upper portion of said frame, and other means including a weighted inverted U-shaped element movably mounted in said frame, one of the arms of said element being engaged in said frame and passing through appropriate registered openings in said tickets, and the other arm of said member being provided with a weight to retain said member in ticket-retaining position and being adapted to retain the stubs of severed tickets. 115

Signed by me this 19th day of July, 1927.

MURDOCK MACDONALD.
